SPRING ASSEMBLY FOR UPHOLSTERY

Abraham N. Lisson, Lynn, Mass., assignor to
 Lisson-Melen Company, Lynn, Mass., a corpora-
 ration of Massachusetts

Application April 13, 1934, Serial No. 720,411

1 Claim. (Cl. 5—269)

This invention relates to a spring assembly for upholstery purposes such as is employed in the seat, back, and side cushioning of furniture, automobiles, railway cars, in mattresses and in other articles.

The object of the invention is to provide an efficient, durable strong, an economical unit and one which may be readily and economically manufactured.

10 The object of the invention is further to provide such a spring assembly composed of expansion helical wire springs with the expansion of the springs limited and with the springs held in definite spaced relation.

15 The object of the invention is further to provide a construction in which the springs are arranged in separated rows and in which the springs in each row are prevented from contacting or rubbing against each other by strips of fabric which at the same time act to limit the expansion of the springs.

20 The object of the invention is further to provide such a spring assembly in which the fabric strips are of a novel construction and are combined in a novel way with the springs so as to produce a strong, durable and efficient arrangement at low cost.

25 These and other objects and features of the invention will appear more fully from the accompanying description and drawing and will be particularly pointed out in the claim.

30 The construction shown in the drawing as a simple and preferred embodiment of the invention is a spring assembly designed for a seat cushion and the applicability of the invention to other purposes will be apparent therefrom. Only a complete spring assembly is shown and it will be understood that the assembly is to be covered or encased with suitable fabric and be padded or otherwise treated in any usual or desired way. The assembly unit is shown as composed of a plurality of similar expansion helical wire springs of cylindrical shape. The cylindrical shape is preferred because such springs give great transverse rigidity to the unit and contract and expand with great uniformity, especially at the margins of the unit. But it will be understood that the hour-glass or other type of expansion helical wire springs may be employed if desired.

35 In the drawing:

40 Fig. 1 is a plan view of the spring assembly unit.

45 Fig. 2 is a view in vertical cross section taken on the line 2—2 of Fig. 1.

50 Fig. 3 is a detail in perspective of one corner of the unit.

The springs are all preferably of the same size and type, each being an expansion spring and each in the form of a helical wire, the dimensions of the springs depending upon the desired use of the assembly.

55 These springs are arranged in rows with the rows spaced apart from each other. In the particular construction illustrated, as shown in Fig. 10 1, there are four such rows each containing five springs.

10 In each row the two springs of each pair of adjacent springs, for example, the pair of springs 1—2, the pair 2—3, the pair 3—4, and the pair 4—5, have their expansion limited and are maintained out of contact by a single endless fabric strip. In each case this fabric strip may be made of any suitable fabric, such, for example, as burlap, and is preferably brought into endless form 20 by sewing together the ends of a straight strip of the fabric. These endless strips of fabric are of a width to give the desired strength and equal to a substantial segment of the springs. The length of the endless strip doubled is made equal 25 to the desired depth or thickness of the spring assembly unit and is substantially less than the height of the springs when fully expanded. Consequently in the completed assembly the springs never stand at their free height but are always 30 somewhat contracted. This gives a highly desirable even yielding quality to the entire unit.

35 Since the construction and arrangement of the separating and expansion limiting feature is the same for each pair of adjacent springs, it will be sufficient to describe that for the pair of adjacent springs 1 and 2. The fabric strip 6 is arranged to encircle the coils of one of the springs, in this case the spring 1, throughout the segment of the spring adjacent the other spring 2. With 40 the endless strip formed from a straight piece of fabric as illustrated, this is very readily done by providing a strip of the required length, compressing the spring, inserting the strip in the spring and stitching the ends 7 together at 8. 45 The uppermost coil of the spring 1 which is encircled by the fabric strip, the uppermost coil of the adjacent spring 2 and both plies of the fabric strip are then secured together. The same thing is also done at the bottom of the unit, that is, 50 the lowermost coil of the spring 1, the lowermost coil of the spring 2, and the two plies of the fabric strip are all secured together. Thus it will be seen that the expansion of both springs is limited by the endless fabric strip and that the two adja- 55

cent springs 1 and 2 are separated by the fabric. Furthermore, since both plies of the endless strip are secured at the top and bottom to the coils of the springs, even if one play should become worn or broken, the other ply will still function to limit the expansion of the springs so that the thickness of the assembly will remain uniform throughout. There is little chance of the unstitched ply breaking and this ply is the one which separates the adjacent springs.

The means employed for securing together the coils of the two adjacent springs and the two plies of the fabric strip is shown in Figs. 1, 2, and 3, wherein the rows of springs are held in the desired spaced relation by a plurality of wire helices 9 which extend transversely of the rows of springs both at the top and at the bottom of the assembly. One of these wire helices passes between each pair of adjacent springs in each row. In this construction each helix 9 at the top has its coils interlaced with the topmost coils of the adjacent springs, as, for example, the topmost coils of the springs 1 and 2, and also is interlaced with both plies of the fabric strip passing around the topmost coil of its spring. This may be done by screwing the helix into place. With this construction it will be seen that the wire helices 9 at the bottom are interlaced in the same manner and that in this case each wire helix 9 acts not only as a means for separating the rows of springs, but also as a means for securing together the two plies of the fabric strip and the coils of adjacent springs as hereinbefore set forth.

Preferably the spring assembly unit is provided at the top and bottom peripheries with a border wire giving a sharply defined peripheral edge to the assembly and serving further to distribute pressure on the assembly among the springs. This border wire may be of any desired construction. In the form illustrated one border wire is secured to the uppermost coils and another to the lowermost coils of the springs and is shown at the ends in the form of straight sections 12 and 13 secured to the spring coils by metal clips 14, and at the sides in the form of wire helices 15 interlaced with the coils of the springs.

It is also desirable that the segments of the springs exposed at the ends of the several rows shall have their expansion limited and for that purpose the exterior segment of each such end spring is shown as provided with an endless fabric strip 16 of the same construction as already described. Preferably also both plies of these endless fabric strips at the exterior of the end coils of the rows, together with the coil of the spring encircled thereby are secured to the border wire at the top and at the bottom and, in the illustrated case, this is done by means of the clips 14 which not only clamp the border wire to the spring but also engage and clamp the endless fabric strip where it encircles the coil of the spring.

The spring assembly may be, and preferably is, reinforced by additional wire struts extending at right angles to the struts such as 9 or 10. In a spring assembly unit of the size employed in cushions, two such additional wire struts will usually be found sufficient and this is the construction shown in the drawing wherein such struts shown as wire helices 17 are employed, one at the top and one at the bottom of the unit. These struts pass approximately centrally of the unit. One of these struts 17 is threaded through the topmost coils of one row of springs, also through the helices 9, and is anchored at its ends to the end springs. The other is connected in the same way at the bottom of a row of springs. These additional struts are advantageous as they hold the assembly in position when it is forced after padding into its cover by a machine such as commonly employed. These struts also act to prevent a spring from bulging out in the assembly if by chance both plies of a fabric strip should become broken.

The construction of this invention enables the size of spring assembly units to be standardized. The rows of springs preferably extend longitudinally of the unit and consequently if springs of substantially three inches in diameter are employed, the unit may be made of any length in multiples of three inches and this covers the usual range of lengths. The rows of springs may be spaced apart to vary the width as desired.

While the border wire has been shown as extending entirely around the periphery at the top and the bottom, it will be understood that all or any portion of the border wire may be omitted, depending upon the use to which the spring assembly unit is to be put.

Having thus described the invention, what is claimed as new, and desired to be secured by Letters Patent, is:

A spring assembly for upholstery comprising a plurality of rows of adjacent expansion helical wire springs, an endless fabric strip for each pair of adjacent springs in each row, the said strip in each case encircling a narrow segment only of the coils of one of the said springs adjacent a bare segment of the coils of the other spring, the springs in said rows positioned with bare segments of the springs in each row opposite bare segments of the springs in each adjacent row, a plurality of wire helices extending transversely of the rows of springs at the top and at the bottom of the assembly, each wire helix having coils interlocking with the end coils of adjacent springs in each row and with both plies of the fabric strips where they pass around the end coils and acting both to secure together the end coils of the said adjacent springs and said plies of the fabric strip and to maintain the rows of springs spaced from each other.

ABRAHAM N. LISSON.
